CLAIM

The ornamental design for a jet engine intake deflection guard, as shown and described.

DESCRIPTION

FIG. 1 is a perspective view of a jet engine intake deflection guard showing my new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof; and,

FIG. 7 is a right side elevational view thereof.

The dashed lines represent portions of an aircraft utilizing a the present design, and forms no part of the claimed invention.
